UNITED STATES PATENT OFFICE.

CELESTINE H. WHITE AND ARTHUR E. WHITE, OF LOS ANGELES, CALIFORNIA.

IRONING-BOARD.

1,279,952.

Specification of Letters Patent. Patented Sept. 24, 1918.

Application filed December 18, 1917. Serial No. 207,736.

to all whom it may concern:

Be it known that we, CELESTINE H. WHITE and ARTHUR E. WHITE, citizens of the United States, residing at Los Angeles, in the county of Los Angeles and State of California, have invented new and useful Improvements in Ironing-Boards, of which the following is a specification.

Our object is to make a knock-down and folding portable ironing-board which is easily manipulated, and simple and inexpensive in construction and operation, and our invention consists in the novel features herein shown, described and claimed.

15 Fig. 1 is a perspective, showing an ironing-board embodying the principles of our invention, set up for use on a table or bench, the supporting legs of the table or bench being broken away to economize space.

20 Fig. 2 is a view analogous to Fig. 1 and showing the ironing-board resting upon the backs of two chairs, the lower portions of the chairs being broken away.

25 Fig. 3 is a vertical fragmentary sectional detail on the line 3—3 of Fig. 2 and looking in the direction indicated by the arrow.

30 Fig. 4 is a fragmentary bottom perspective of one end of the ironing-board shown in Figs. 1 and 2, and showing the legs unfolded for use upon a table or bench, as in Fig. 1.

35 Fig. 5 is a view analogous to Fig. 4, and showing the legs folded, as when the ironing-board is to be used upon a chair or horse, as in Fig. 2.

40 Fig. 6 is a fragmentary perspective from the bottom and showing the means for rigidly and detachably joining the two sections of the board together.

45 Figs. 7 and 8 are perspectives showing a pair of the connecting hooks, shown in Fig. 6 in position about to go together.

The ironing-board body 1 consists of the board sections 2 and 3 abutting together end to end upon the line 4, there being reinforcing strips 5 and 6 across the abutting ends to hold the boards from warping and to make smooth edges. The boards 2 and 3 are detachably joined together and held in a straight line by pairs of hooks 7 and 8. The pair of hooks 7 consist of the interlocking members 9 and 10. The hook 9 comprises a flat portion 11 secured to the bottom of the board 2 by screws 12, the curved portion 13 extending downwardly and inwardly from the portion 11, the second flat

portion 14 extending from the portion 13 parallel with the portion 11, the return bend 15 extending from the portion 14, and the return portion 16 extending backwardly from the return bend 15 parallel with the portion 14 so as to make an off-set hook. The hook 10 comprises the flat portion 17 secured to the bottom face of the board 3 by screws 18, the return bend 19 extending from the inner end of the portion 17, and the return portion 20 extending outwardly from the return bend 19 parallel with the portion 17. The hooks go together edgewise, the return portion 16 fitting between the portions 17 and 20, and the return portion 20 fitting between the portions 14 and 16, and the hooks being so located that when they are pushed together edgewise the boards 2 and 3 fit closely together and are rigidly held in a straight line.

The hook 8 is identical in construction with the hook 7. The folding legs 21 and 22 are attached to the lower faces of the outer ends of the boards 2 and 3 so that when the legs are unfolded, as in Figs. 1 and 4, they may rest upon any suitable flat face, as the table 23, and support the board in its extended position.

The folding legs 21 are shown in detail in Figs. 4 and 5. Hinges 23 and 24 are attached to the bottom of the board 2 and wooden blocks forming the legs 25 and 26 are attached to the hinges. The ends of the legs 25 and 26 are oppositely and correspondingly beveled, and fabric pads 27 are attached to the upper end faces to engage the lower face of the board 2 when the legs are unfolded and to engage one side of the chair back when the legs are folded and the board is in use on chairs as in Fig. 2.

A retaining cleat 28 is secured to the lower face of the board 2 in a transverse line and a fabric pad 29 is secured to the lower face of the board 2 and to the inner and lower faces of the cleat 28, to engage the chair back, the object being not to mar the chair and to prevent rattling.

A cord loop 30 is passed through eyes 31 secured to the inner edges of the legs 25 and 26 and through a ring 32, the loop being loose enough to allow the ring 32 to be hooked over the screw-eye 33 and hold the legs 25 and 26 in their unfolded position, as in Fig. 4, and to allow the ring 32 to be hooked over the screw-eye 34 and hold the legs 25 and 26 in their folded position, as in

Fig. 5; the screw-eye 33 being located at the end edge of the board, and the screw-eye 34 being located to extend downwardly from the board in front of the legs. The details of the legs 22 are identical with the legs 21 already described, and it is thought they need not be further shown or described. When it is desired to put the ironing-board out of use, the legs 21 and 22 may be folded to the position shown in Fig. 5, and the boards 2 and 3 may be separated by pushing one edgewise relative to the other to bring the hooks out of engagement, then the boards may be placed face to face, one on top of the other, or handled in any other suitable way. Likewise, when it is desired to assemble the board for use the boards 2 and 3 are placed together end to end and one moved sidewise relative to the other to assemble the hooks, and then the legs 21 and 22 may be unfolded for mounting the board upon a table or bench, as shown in Fig. 1, or the legs may be folded for mounting the board upon chairs or horses, as shown in Figs. 2 and 5.

While we have shown the preferred construction of our ironing-board, as now known to us, it will be understood by those skilled in the art that various changes in the combination, construction and arrangement of parts may be made without departing from the spirit of our invention as claimed.

Copies of this patent may be obtained for five cents each, by addressing the "Commissioner of Patents, Washington, D. C."

We claim:

In a knock-down ironing board, two board sections adapted to abut together end to end in a straight line, and two pairs of interlocking hooks secured to the bottoms of the board sections for holding the board sections removably together; each pair of interlocking hooks comprising two members, the first member comprising a flat portion secured to the bottom of one board, a bent portion extending downwardly and inwardly from the flat portion, a second flat portion extending from the bent portion parallel with the first flat portion, a return bend extending from the second flat portion, and a return portion extending backwardly from the return bend parallel with the second flat portion, and the second member comprising a flat portion secured to the bottom of the other board, a return bend extending from the inner end of the flat portion, and a return portion extending outwardly from the return bend parallel with the flat portion; so that the members will go together edgewise, the return portion of the first member fitting between the flat portion and the return portion of the second member.

In testimony whereof we have signed our names to this specification.

CELESTINE H. WHITE.
ARTHUR E. WHITE.
